UNITED STATES PATENT OFFICE

2,181,267

RECIPROCATING GUIDE HEAD FOR YARN
PACKAGING DEVICE

William J. Elvin, Cumberland, Md., and Joseph L. Killoran, Drummondville, Quebec, Canada, assignors to Celanese Corporation of America, a corporation of Delaware

Original application August 30, 1934, Serial No. 742,108, now Patent No. 2,048,787, dated July 28, 1936. Divided and this application February 13, 1936, Serial No. 63,731

3 Claims. (Cl. 242—43)

This invention relates to a yarn packaging device and more particularly to such a device that draws yarns from a package such as a bobbin, imparts a twist to the yarn and winds the same into a cross-wound package, such as a cheese. This invention relates particularly to the head of such a device including the driving and other mechanism for winding the yarn onto the cross-wound package.

10 An object of the invention is a commercially practical device which will twist and package fine filaments or yarns such that the resulting package may be large, say 1½ lbs., firm, free from tendencies to fluff at the ends and which is uniform in tension, without soft spots. Another object of the invention is a device so designed that the package formed thereon is uniform throughout. Other objects of the invention will appear from the following detailed description and drawing.

20 This application is a division of our application S. No. 742,108, filed August 30, 1934, which has issued as Patent No. 2,048,787.

25 In the drawing wherein like numbers refer to the same or equivalent elements,

Figure 1 is a perspective view of a reciprocating guide head showing the driving means therefor.

Figure 2 is a side elevation in detail of the drive mechanism shown in Figure 1, and

Figure 3 is an end view partially in section taken on the line 8—8 of Figure 2.

In the cross-winding of packages, such as cheeses, the yarn is guided to the take-up package by means of a reciprocating guide member. This guide member reciprocating transversely to the direction of rotation of the take-up package directs the yarn or thread onto the package in a spiral form one end to the other and back. If the rate of reciprocation is constant relative to the rate of rotation, the point of reverse of the yarn will fall in ever so many cycles on the point of reverse of a former laid increment of yarn. In this manner a cross-wound package is formed the ends of which are not uniformly solid but contain hard spots where the points of reverse of the yarn are one above the other and soft spots where the points of reverse of the yarn do not occur. Some packages, depending upon the ratio of the traverse to the revolutions of the yarn, may contain the points of reverse in lines radiating from the center making a package very easily fluffed, i. e., increments of yarn forming arcs across the end of the package. These types of packages can-

not be roughly handled nor even employed in certain types of textile operations.

In employing the device forming this invention, however, the ratio of the reciprocation of the guide means is not constant in respect to the rate of rotation of the take-up package and, therefore, the points of reverse do not fall in limited areas on the end of the package but are evenly distributed throughout the area. This forms a solid package that may be shipped or otherwise handled and applicable to textile operations without fluffing at the ends. This is accomplished not by a progressive change in the ratio referred to, which would lead to the same fault as a constant ratio, but by varying the ratio first to one side and then the other of a mean ratio.

In accordance with our invention, we have devised a method and device for accomplishing the same that winds yarns into cross-wound packages, which packages are solid and free from ununiform ends. This device is designed for use in connection with the complete winding and spinning device shown in Figure 1 of the parent case.

For guiding the thread onto the take-up package 25 there is provided a reciprocating guide member 21 that causes a cross-winding of the thread upon the package. It is desirable that the reciprocation, and thus the laying on of the thread upon the package, have a mean speed 30 which is constant relative to the peripheral speed of the take-up package, yet a speed that varies from faster to slower than the mean speed so that the points of reverse of the thread upon the package will not fall with too great a frequency upon 35 the same or about the same axial line and result in a package that has an ununiform end. This may be accomplished by the driving means for the cam that governs the reciprocation of guide 21.

The term "yarn" and "thread" are here used as substantially synonymous and may include fibers or filaments of any suitable materials such as filaments of organic derivatives of cellulose, regenerated or reconstituted cellulose, silk or mixtures of these or the yarns may be formed of fibers twisted or otherwise held together of cotton, wool, flax and the like.

In the drawing there is shown part of a device constructed in accordance with our invention, which device employs a simple form of a drive for imparting a variable reciprocation to thread guides 21. This drive device is adapted for use on automatic twisting devices and especially on the type shown in Figure 1 of the parent case. 55

From any suitable source, and preferably from a source connected with the supply package drive mechanism, rotation is imparted to the shaft 33, upon which is mounted a friction roll 23 that supports and turns the take-up package 55. The friction roll 23 may be of sufficient length to support and rotate one or several take-up packages.

On shaft 33 is fastened a sprocket wheel 64. Suitably journaled in the main frame is a shaft 116 lying parallel to and beneath shaft 33, said shaft 116 having fastened thereto a sprocket wheel 117 that registers with and is driven from sprocket wheel 64 by a sprocket chain 118, thus imparting a positive movement to shaft 116 in timed relation to the peripheral speed of the take-up package 55.

Fastened on shaft 116 by means of a key 119 or other suitable means are two gears 120 and 121. Gear 120 is slightly larger than gear 121.

20 A shaft 88 suitably journaled in a drum cam box 95 that is a part of the main frame has fastened thereto a drum cam 87. The shaft 88 has mounted thereon and rotatable with respect thereto two gears 122 and 123 that register with 25 and are driven from gears 121 and 120, respectively. The diameter of gear 123 is less than the diameter of gear 122 so that in registering with gears 121 and 120 the shafts 116 and 88 may be substantially parallel.

30 Fastened to or made a part of gear 122 is an elliptical gear 124 eccentrically mounted on shaft 88. Gear 123 is formed with a bearing member 125 in which is mounted a shaft 126 adapted to rotate therein. The shaft 126 has fastened 35 thereto as by a key 127 or made integral therewith an elliptical gear 128 mounted eccentrically of shaft 126 and in registry with and driving relation to elliptical gear 124. On the opposite end of shaft 126 is a gear 129 fastened thereto by 40 means of a key or other suitable means.

Keyed to, or otherwise suitably fastened in driving relation to shaft 88 is a gear 130 that registers with and is in driving relation to gear 129 on shaft 126. The gear 130 imparts rotation to 45 shaft 88 which in turn rotates drum cam 87. On drum cam 87 there are two cam ways 92 and 93 in the latter of which a roller pin 91 is adapted to be guided. Pin 91 is suitably fastened to a slide head 90 that is fastened by adjustable rod 50 96 to the reciprocating thread guide holder rod 89.

The action of the drive mechanism is as follows: Shaft 116 is driven by sprocket chain 118 from the friction roller drive shaft 33. The two 55 gear wheels 122 and 123 then rotate at slightly different speeds so that there is a relative motion between them to give one relative revolution for each complete cycle of traverse variation. The major and minor axes of the elliptical wheels 60 may be chosen to give the required variation of traverse on either side of the mean speed. The elliptical wheel 128 will make one revolution for each revolution of the wheel 122 relative to the wheel 123. Since the wheels 128 and 129 are both 65 positively fastened to the same shaft, it follows that the wheel 130 must make one revolution relative to the wheel 123 for each relative revolution of the wheel 122, but since the wheel 130 gets this motion through the elliptical pair of 70 wheels, its speed will not be uniform. The net result is to superimpose a variable velocity onto the

uniform velocity of revolution transmitted to the wheel 123. The mean velocity of revolution of the shaft 88 and the cam drum 87 will be the same as that of the wheel 122, but there will be a slow relative backward and forward movement 5 of the shaft 88 with relation to the wheel 123.

It is to be understood that the foregoing detailed description is given merely by way of illustration and that many variations may be made therein without departing from the spirit of our 10 invention.

Having described our invention, what we desire to secure by Letters Patent is:

1. In a machine for producing cross-wound packages of yarn, the combination with means for 15 winding the yarn on the package at a constant speed, of means for traversing the yarn on the package comprising a shaft, a drum cam mounted on said shaft, a traverse guide rod adapted to be reciprocated by said drum cam, a second shaft 20 driven through said winding means, a plurality of gears attached to said second shaft, floating gears supported on the drum cam shaft and adapted to mesh with the gears on said second shaft, and eccentrically mounted elliptical gears 25 attached to said floating gears, said eccentrically mounted elliptical gears being adapted to rotate the drum cam, the construction and arrangement being such that the drum cam reciprocates the traverse guide rod at a variable speed. 30

2. In a machine for producing cross-wound packages of yarn, the combination with means for winding the yarn on the package at a constant speed, of means for traversing the yarn on the package comprising a shaft, a drum cam 35 mounted on said shaft, a traverse guide rod adapted to be reciprocated by said drum cam, a second shaft driven through said winding means, a plurality of gears of different diameter attached to said second shaft, floating gears of different diameter supported on the drum cam shaft and adapted to mesh with the gears on said second shaft, and eccentrically mounted elliptical gears 40 attached to said floating gears, said eccentrically mounted elliptical gears being adapted to rotate the drum cam, the construction and arrangement being such that the drum cam reciprocates the traverse guide rod at a variable speed. 45

3. In a machine for producing cross-wound 50 packages of yarn, the combination with means for winding the yarn on the package at a constant speed, of means for traversing the yarn on the package comprising a shaft, a drum cam mounted on said shaft, a traverse guide rod 55 adapted to be reciprocated by said drum cam, a second shaft driven through said winding means, a plurality of gears attached to said second shaft, floating gears supported on the drum cam shaft and adapted to mesh with the gears on said second shaft, eccentrically mounted elliptical gears 60 attached to said floating gears, and a gear attached to said cam shaft, said elliptical gears being adapted to rotate the drum cam through the said gear attached to said drum cam shaft, the construction and arrangement being such that the drum cam reciprocates the traverse guide rod at a variable speed. 65
